UNITED STATES PATENT OFFICE.

HENRY VILM, OF KANSAS CITY, MISSOURI.

MILLSTOCK PURIFIER.

Application filed April 26, 1922. Serial No. 556,592.

To all whom it may concern:

Be it known that I, HENRY VILM, a citizen of the United States, residing at Kansas City, in the county of Jackson and State of Missouri, have invented certain new and useful Improvements in Millstock Purifiers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to purifiers and particularly to a gravity and return air purifier for mill stock in flour mills.

The primary object is to provide an improved purifier which will separate and grade materials of different specific gravities, the material especially contemplated being known as "middlings."

20 Novel means is provided for separating the lighter particles from the heavier particles, allowing the heavier particles to gravitate into chambers or bins to be subsequently carried off to reduction rolls, bolters or other appropriate machines.

25 Means is also provided for maintaining a substantially closed air circulation so that the air may be used continuously; there being means provided, however, to augment the supply to take care of whatever leaks occur.

30 There is a special advantage in using the air repeatedly because after the air has taken up a certain amount of moisture, it will not absorb any more moisture from the mill stock whereas if a continuous circulation

35 of air is maintained through the machine, that is, if air is taken in at one end of the machine and exhausted at the other, not only will there be a considerable loss in heat but the incoming fresh air will absorb a considerable amount of moisture in the stock and cause it to become brittle, thereby increasing the amount of "ash" over that which would be present where a closed, recurring air circuit is used.

40 Another important feature of the invention over similar devices which have oscillating or vibrating parts is that the liability of flouring due to attrition in passing through purifiers will be materially reduced.

In actual practice I have found that the attrition losses are not appreciable in my device, whereas they are quite a factor in devices which agitate the stock so that the particles rub one against the other and cause flouring or ash.

45 The novel construction of the invention as well as the manifold advantages will be apparent by reference to the following description, reference being had to the accompanying drawings, in which—

50 Fig. 1 is a perspective view of a purifier constructed in accordance with my invention.

Fig. 2 is a vertical, longitudinal, sectional view through the purifier, the air conduit 70 from the air impeller being shown in elevation, and

55 Fig. 3 is a sectional view of the discharge conveyor and the upper end of the chute with which it communicates.

60 The purifier is shown as comprising an approximately rectangular hollow casing, divided into a plurality of separation chambers 1, 2, 3, 4 and 5 respectively. The casing is generically designated 6 and the bottom or floor thereof is divided into the hoppers or separation chambers 5, 1, 2 and 3 in the order named. The respective chambers 5, 1, 2 and 3 are provided with valved outlets 7, 8, 9 and 10 in the vertexes of the hoppers. 65 The valves are shown as consisting of rotatable cylinders 11, having radial wings or blades 12, providing pockets 13 to feed the material into the respective chutes 14, 15, 16 and 17, which may lead to the reducing rolls, 70 bolters or other appropriate machines.

75 Dividing the hopper 5 from the hopper 1 is an upstanding rigid baffle 18; the hopper 1 is divided from the hopper 2 by a hinged baffle 19; the hopper 2 is divided from the 80 hopper 3 by a hinged upstanding baffle 20 corresponding to the baffle 19 and the baffles 19 and 20 are adapted to be swung on their hinges from the exterior of the machine by the crank arms 21 and 22 fixed to the shafts 23 and 24 of the respective baffles 19 and 20 so that the angles of inclination of the baffles 19 and 20 may be varied.

85 At the top of the machine is a feed hopper 25, which receives the stock from any suitable source, preferably a chute or conveyor. One side of the hopper 25 is provided with a hinged wall 26, provided with weights 27

so that the wall or gate 26 will normally lie against the corrugated feed roll 28 extending transversely across the bottom of the hopper 25 and which feeds the material onto the inclined chute 29, which is, in effect, a continuation of one wall of the hopper.

The chute or board 29 is provided at its lower end with an upturned discharge plate 30, which terminates adjacent to and below the upper edge of the baffle or wall 19 so that when the stock is fed by the roller 28 onto the board 29 and slides over the surface thereof, it will acquire sufficient velocity to be directed upwardly and over the upper edge of the hinged valve plate 30' of the hopper 19, bridging the gap 31 between the plate 30 and the baffle 19, allowing the air to carry the lighter particles into the hopper 2, the heavier particles gravitating into the receptacle or hopper 1.

In other words, the air will only carry the lighter particles beyond the gap 31 and into the hopper 2. The lighter particles will strike the depending baffle board or wall 32 interposed between the baffles 19 and 20 and be directed in an opposite direction to said baffles so as to form a tortuous passage as indicated by the arrows.

The air will pass down below the lower edge of the baffle 32 and over the baffle 20, allowing the heavier particles passing between 19 and 20 to drop into the hopper 2 but carrying the lighter particles over the baffle 20 into the hopper 3.

35 The current of air then passes up through the superposed hopper 33 above the hopper 3, which encloses the separation chamber 4, the entrance being through the valved opening 34. In doing this, it carries with it the particles which are too light to gravitate into the hopper 3 and most of them will gravitate to the bottom of the hopper 33 and be carried by the screw conveyor 35 to the chute 36.

40 By reference to Fig. 2 it will be observed that the impeller or fan 37 is at the top of the hopper 33 and that it communicates with the chamber 4 through a side inlet 38. The fan will cause a slight vacuum to be formed in the chamber 4 to draw the lighter particles thereinto and some of the finest particles will pass into the fan 37 and be forced by the impeller 39 through the return conduit 40 into the space 41, above the hopper 5, where the solids will strike against the baffle 18 and cause the finest particles to drop into the hopper 5 to be discharged into the conveyor 14 so that practically air only will enter beneath the board 29 into the hopper 1 to act upon the stock discharged from the plate 30.

45 The gate 42, covering the opening 34, is a deflector plate, tending to direct the major portion of the finer particles entering the chamber 4 onto the conveyor 35, it

being understood that only the very finest particles are sucked into the fan 37 to be discharged into the hopper 5.

It will be apparent that a continuous, recurring circulation of the same air will take place through the casing 6.

All of the parts are so mounted that there will be very little leakage but, obviously, it will be impossible to entirely eliminate leakage of air in any machine having operating parts, so in order to augment the supply of air, I have provided at the dome portion 43 constituting the roof of the chamber 4, an inlet consisting of an upstanding perforate tube 44, having a sleeved cap 45 fitting over the same so that the effective port area of the air inlet tube can be controlled to allow only enough air to enter the casing 6 as is necessary to compensate for the amount of leakage.

85 The air impeller may be driven from a belt 46, passing around a pulley 47 on the shaft 48, the belt being shown as also passing over a pulley 49 on a shaft 50, driven by a belt 51, which passes over a pulley 52 thereon. The end of the shaft 50 distant from the one carrying the pulley 49, carries a pulley 53, which drives a belt 54 passing around a pulley 55 on the shaft 56 for the roller 28, so that the feed roller 28 will be constantly driven during the time that the fan is driven and the shaft 50 also carries a pulley 57, which drives a pulley 58 on the shaft 59 through the medium of the belt 60. The shaft 58 carries pinions 61, which mesh with beveled gears 62 on the ends of the valve cylinders 11 for the respective hoppers 5, 1, 2 and 3 so that the valves 11 will be constantly rotated to feed the materials from the hoppers into the chutes 14, 15, 16 and 17.

90 In order to externally control the gate 42 I have provided a crank arm 63 on the end of the shaft 64 for the deflector valve or gate 42.

95 The screw conveyor 35 is provided with a shaft 65, which extends through one side of the machine and which is provided with a pulley 66 driven from the pulley 67 on shaft 48 through the medium of a belt 68.

100 When the parts are assembled and the machine is operating, mill stock will be fed into the hopper 25, the rate being controlled by the weighted gate 26 and the rotating feed roller 28. As it gravitates down the inclined chute or board 29, it will be directed upwardly toward the upper edge of the baffle 19; the air discharging from the conduit 40, constituting the discharge end of the fan, will pass through the chamber 41, over 18 and up through the gap 31, carrying the lighter particles into the hopper or chamber 2 and allowing the heavier particles to gravitate into the hopper or chamber 1, the lighter particles being progressively separated in 115

the chambers or hoppers 2, 3 and 4 and finally the lightest particles will be deposited in the chamber 5, as will be apparent from the foregoing description.

- 5 The proportion of the flow passing from the plate 30 to the upper edge of the baffle 19 can be controlled by swinging the hopper 9 on its hinge; that is, if the size of the gap 31 is increased, a greater percentage of the
 10 stock will be permitted to gravitate into the hopper 1 than would be possible if the gap were narrowed. The same is true with respect to the baffle 20 and the positions of these baffles can be conveniently controlled
 15 through means of the crank arms 21 and 22.

On the chute 36 is a spring-pressed valve 69 which tends to close the outlet 70 for the conveyor 35 so as to prevent leakage into the machine. The valve 69, however, will
 20 open under the action of the material discharged by the conveyor 35 but the valve will only open enough to allow the discharge of the flour. Therefore, the discharge end 70 is practically sealed at all times because
 25 the flour, piling up at the exit end of the discharge 70, will, in itself, act as an air seal.

From the foregoing it will be apparent that with the construction of purifier contemplated by my invention the heavier particles of stock can be inversely separated from the heaviest to the lightest, over a range dependent upon the number and arrangement of the hoppers, and that the proportion of the stream of material to be re-

ceived in any one hopper can be controlled by arranging the positions of the baffles. It will also be observed that the air can be repeatedly used so as to maintain the necessary moisture in the stock and without liability of drying it out during the separation operation, it being only necessary to add such amounts of air as are required to compensate for natural losses due to leakage, which is bound to occur in any machine in which there are movable parts.

What I claim and desire to secure by Letters-Patent is:

A device of the class described comprising a closed casing, a plurality of communicating separating chambers in the bottom of the casing having open upper ends, means for feeding mill stock into the space above the second chamber, means for feeding air into the first chamber, means for directing air from the first chamber into the second chamber to permit it to pass therethrough into a third chamber, means for directing air from the third chamber into a fourth chamber, and means for returning some of the mill stock from the fourth chamber to the first chamber, said means comprising a chamber located above the fourth chamber and having an inlet to one side thereof and a return conduit having an air impeller therein, the return conduit leading from the last mentioned chamber to the first chamber, and discharging into the top thereof.

In testimony whereof I affix my signature.
 HENRY VILM.
